UNITED STATES PATENT OFFICE.

WILLARD N. PACKER, OF SAN PEDRO, CALIFORNIA.

SEPARATOR.

Application filed February 4, 1924, Serial No. 690,351. Renewed October 13, 1925.

To all whom it may concern:

Be it known that I, WILLARD N. PACKER, a citizen of the United States, and resident of San Pedro, in the county of Los Angeles, State of California, have invented new and useful Improvements in a Separator, of which the following is a specification.

This invention relates to a device for operating upon mixtures containing material differing in densities and for separating the lighter from the heavier ingredients. Thus, mixtures of sand and gold or other mineral matter may be separated into their ingredients.

More specifically, the invention comprises one or more cylinders which receive the mixture and are subjected to a planetary motion during which separation is effected.

The primary object of this invention is to provide a structure to function as aforesaid. Other objects are to provide a structure of the character described which is strong, durable, and requires a minimum of attention.

These objects together with other objects and corresponding accomplishments are obtained by means of the embodiment of my invention illustrated in the accompanying drawing, in which:

Fig. 1 is a front elevation of a complete machine; Fig. 2 is a side elevation; and Fig. 3 is a section as seen on the broken line 3—3 of Fig. 1.

Referring more particularly to the drawing, a frame 4 supports the several parts of the machine. Journalled in the top of the frame is a vertical shaft 5, which is fixed at its lower end to a yoke 6. The yoke is journalled on the bottom of the frame and is provided with laterally extending arms 7. Fixed to the upper end of the shaft 5 is a bevel gear 8. Mounted upon the frame 4 at opposite sides of the shaft are bearing standards 9, in which is journalled a shaft 10. Fixed to the shaft 10 is a bevel gear 11 meshing with gear 8 so that motion will be transmitted from shaft 10 to shaft 5. At one end of the shaft 10 is a hand crank 12 providing for manual operation of the machine, and at the other end is a drive pulley 13, whereby the machine may be connected to a driving machine such as a motor.

Fixed to the shaft 5 is a hopper 14, open at the top and having chutes 15 extending from the sides thereof adjacent the bottom of the hopper, the chutes delivering to cylinder buckets 16, the latter being open at the top

and having inturned flanges or lips 17. The buckets are secured to shafts 18, which are journalled at the upper ends in swivel bearings 19. The lower ends are journalled in the arms 7.

Fixed to the shafts 18 are rolling gears 20. Journalled on the arms 7 and meshing with the gears 20 are idler pinions 21. Meshing with the pinions 21 is a stationary base gear 22, which may have a shaft extending through the yoke and fixed to the frame 4.

Mounted upon the top of the frame and suitably supported by braces is a delivery hopper 23, from which the mixture may be conducted to the hopper 14. A slide gate 24 controls the flow of material from the delivery hopper to the receiving hopper.

The mixture which is to be operated upon is delivered to the hopper 23, the gate 24 being closed. The machine is now set in operation by rotating the shaft 10. This motion is transferred to the shaft 5, revolving the yoke 6 and the cylinder buckets thereon. The base gear 22 being stationary will cause the idler pinions 21 to be rotated. In turn, the movement is transmitted to gears 20, and the buckets 16 are thereby caused to rotate. Thus, the buckets are both rotated and revolved. The motion is a planetary or epicycloidal motion. Due to the idler pinions, the buckets 16 are given a rotary motion in a direction opposite to their revoluble motion which causes a rolling of the contents. The gate 24 is opened sufficiently to feed the material to hopper 14 and it passes from the latter through chutes 15 to the buckets. The centrifugal force due to the revolution of the bucket tends to maintain the material at the outer side, and a further agitating and centrifugal force is obtained by rotation of the buckets about their own axes. The lighter material climbs toward the top of the bucket and finally passes over the flanges 17 being thrown outwardly. The heavier materials remain in the bucket. During the operation the contents are rolled in the cylinders.

It is obvious that the device may be used for separating clay and dirt from beans, peas, and the like. It may also be used for separating light weight seed from the more solid, the latter having a higher germinating quality. Another use to which the device may be put is separating cull nuts from the good ones. However, the machine is especially adaptable for separating float, flour,

or flake gold from sand while in a dry condition. It is also adaptable for wet washing of coarser metals.

The double centrifugal effect also scours the material being separated. Thus, gold coated with silicate or oxidized is cleaned to make it better for action upon it by quicksilver or mercury. The machine may be put to various other uses.

10 While I have shown my invention embodied in a structure having spur gears and pinions, my invention is not limited to such structure, as pulleys and belts, sprocket wheels and chains may be substituted therefor so as to revolve and rotate the cylinders in opposite directions.

What I claim is:

1. A separator comprising a revoluble arm, a stationary base gear mounted at the axis of said arm, a rolling gear journalled upon said arm, an idler pinion journalled on said arm and in mesh with said gear, and an imperforate cylinder open at the top and closed at the bottom secured to said rolling gear so as to be rotated and revolved therewith, said cylinder having its axis declined upwardly and outwardly.

2. A separator comprising a frame, a vertical shaft journalled in said frame, a yoke secured to said shaft and having laterally

extending arms, a stationary base gear disposed with its axis coinciding with the axis of said shaft, rolling gears journalled on said arms, idler pinions journalled on said arms and gearing said base gear to said rolling gears, imperforate cylinders open at their upper ends and closed at their lower ends, and secured to said rolling gears so as to be rotated and revolved therewith, said cylinders having their axes inclined upwardly and outwardly.

3. A separator comprising a frame, a vertical shaft journalled in said frame, a yoke secured to said shaft and having laterally extending arms, a stationary base gear disposed with its axis coinciding with the axis of said shaft, rolling gears journalled on said arms, idler pinions journalled on said arms and gearing said base gear to said rolling gears, imperforate cylinders open at their upper ends and closed at their lower ends secured to said rolling gears so as to be rotated and revolved therewith, said cylinders having inturned flanges at their upper ends and their axes being inclined upwardly and outwardly.

In witness that I claim the foregoing I have hereunto subscribed my name this 26th day of January, 1924.

WILLARD N. PACKER
